AUTOMATIC GRINDING DEVICE

Filed Dec. 22, 1938

UNITED STATES PATENT OFFICE

2,164,155

AUTOMATIC GRINDING DEVICE

Arthur Lemay, New York, N. Y.

Application December 22, 1938; Serial No. 247,153

8 Claims. (Cl. 51—101)

My present invention relates to lens grinding machines and more particularly to an attachment for existing machines to enable the elimination of waste motion in such machines thus speeding up the grinding process.

In the accompanying specification I shall describe, and in the annexed drawing show, an illustrative embodiment of the present invention. It is however to be clearly understood that the present invention is not limited to the exact details of construction herein shown and described for purposes of illustration only inasmuch as changes therein may be made within the scope of the claims hereto appended without the exercise of invention.

In the accompanying drawing,

Fig. 1 is a plan view of a lens grinding machine provided with an attachment constituting the aforesaid illustrative embodiment of the present invention.

Fig. 2 is an enlarged side view looking along line 2—2 of Fig. 1, and

Fig. 3 is a similar view looking along line 3—3 of Fig. 1.

Before describing my invention in detail, I deem it advisable briefly to refer to the prior art in the field to which the present invention relates and to point out the disadvantages thereof, and the manner in which the present invention overcomes the same.

In the existing lens grinding machines, the lens to be ground is continually rotated at a slow rate of speed. Obviously, some portions of the lens become finished before others due to many reasons. For one thing, lenses are not generally of a uniform thickness throughout so that the thin portions are easier to grind than those which are thicker, the thin portions thus becoming finished first. However, in the existing machines, in view of the continuous rotation of the lens, there are times when the machine is operating but no grinding is being done and no grinding can be done until another high spot or unground portion of the lens is presented to the grinding wheel. This waste motion needlessly extends the time necessary to complete the grinding job.

By means of the present invention, I am able to slightly alter the existing machines so as to have the lens rotate only when grinding at any point along the periphery of the lens has been finished; and then the lens only rotates until a portion not yet finished is presented to the grinding wheel. Thus, instead of there being continuous rotation of the lens, there is prac-

tically continuous grinding of the lens thus eliminating waste motion and considerably shortening the time necessary to finish the grinding. As a matter of fact, I have found that the grinding time is reduced to one-quarter of that necessary with existing machines.

Other objects and advantages of the present invention will readily occur to those skilled in the art as the detailed description progresses.

Referring now more in detail to the aforesaid illustrative embodiment of the present invention and with particular reference to the drawing illustrating the same, the numeral 5 generally designates a lens grinding machine which includes a frame 6 having slidably journaled therein a shaft 7. One end of the shaft is provided with a pulley 8 over which is trained an endless belt 9 connected with any desired source of power.

The shaft 7 also carries a conventional grinding wheel 10 which in addition to being rotatable is given a reciprocating side-to-side motion. The latter is accomplished through the following means:

The shaft 7 is provided with a pulley 11 over which is trained an endless belt 12, one end of which engages another pulley 13 which, through the worm 14, worm wheel 15 and arms 16 impart a reciprocating motion to the shaft 7.

All of this construction is conventional and constitutes no part of the present invention.

The other end of the looped belt 12 is trained over a pulley 17 fixed upon a shaft 18 the inner end of which is engaged by a fork 19 attached to the armature 20 of an electro-magnet 21. The shaft 18 is not only rotatably mounted in the frame 6 but it is in addition, slidably therein. On the outer end of the shaft 18 is a pinion 22 adapted, when the shaft 18 is moved outwardly through the action of the electro-magnet 21, to engage a gear 23 fixed upon a shaft 24 rotatably mounted in the frame 6. The pinion 22 constitutes a clutch. The inner end of the shaft 24 is provided with a pinion 25 in mesh with a gear 26 fixed upon a shaft 27 journaled in the frame 6. Opposed to the shaft 27 is another shaft 28 likewise journaled in the frame 6 and having fixed on the outer end thereof a gear 29 in mesh with a pinion 30. The latter may either be fixed upon a separate stub shaft or it may be fixed upon a continuation of the shaft 24 which carries the pinion 25.

The facing ends of the shafts 27 and 28 are provided with jaws 31 of a vise adapted to clamp therebetween the piece of glass 32 or unground

blank which it is desired to shape into a lens and a pattern wheel 33 which is adapted to determine the size and shape of the lens. The latter is made of metal and is adapted, as will 5 hereinafter be more fully explained, to complete a certain electrical circuit so as to operate the electro-magnet 21 and thus control the rotation of the lens 32.

Fixed to the frame 6, and insulated therefrom 10 is a contact plate 34 connected by a wire 35 to one end of the electro-magnet 21. The other end of the electro-magnet is connected by a wire 36 to a source of electrical current 37 and the other end of the source of current is grounded 15 by a wire 38 to the frame 6 of the machine. Inasmuch as the pattern wheel 33 is likewise grounded to the frame 6 the electrical circuit through the electro-magnet 21 can only be completed when the pattern 33 engages the contact plate 34.

The device is completed by providing a pawl 39 in contact with the gear 33, the purpose of which is to provide an audible signal continually in operation when the grinding has been completed.

This completes the description of the aforesaid illustrative embodiment of the device of the present invention and its mode of use may be briefly summarized as follows:

30 Normally, no current is flowing through the electro-magnet 21 so that the pinion or clutch 22 is not engaged with the gear 23. Thus, although the pinion 22 is continually rotating, the gear 23 and the train driven thereby, including 35 the lens 32, is not rotating.

When it is desired to grind the lens, an unground blank comprising a piece of glass roughly having the shape of the finished lens is clamped between the jaws 31 together with a pattern 33 of the desired size and shape. By any preferred 40 means, such as a tension spring 40 the periphery of the lens is maintained in contact with the rotating grinding wheel 10. At this time, the pattern 33 is not in contact with the plate 24. 45 Thus, the portion of the lens presented to the wheel 10 is ground but the lens remains stationary. As the grinding continues, the lens moves closer to the wheel 10 under the tension of the spring 40 and when a sufficient amount of 50 the glass has been ground away the pattern 33 comes into contact with the plate 34 and the electrical circuit through the electro-magnet is completed. Thus the pinion 22 is shifted into 55 mesh with the gear 23 to permit rotation of the latter and the train and lens geared thereto. This rotation continues only until a high spot or unground portion of the lens contacts the wheel 10; for, at this time, the pattern 33 will be moved away from the plate 34 to break the electrical 60 circuit through the electro-magnet, which permits the armature 20 to return to its normal position, disengaging the pinion 22 from the gear 23. The portion of the lens 32 then being presented to the grinding wheel 10 will be ground 65 until, again, a sufficient amount thereof has been ground away to permit contact between the pattern 33 and plate 34. The device will then operate as before described. This intermittent grinding and rotation will continue until the lens 70 has been ground away sufficiently to permit continuous contact between the pattern 33 and plate 34.

This results in a continuous circuit through the electro-magnet 21 and this causes continued rotation of the gear 23 and the lens 32. The con-

tinuous sound of the teeth of the gear 23 moving over the pawl 39 will advise the operator that the grinding is completed.

This completes the description of the mode of use of the device of the present invention and 5 it will be noted from all of the foregoing that the device is simple in construction, easy and economical to fabricate and assemble and is admirably adapted to perform the intended functions.

10 Other objects and advantages of the present invention will be obvious to those skilled in the art to which the present invention relates.

What I claim as my invention is:

1. In combination with a lens grinding machine having a constantly rotating grinding wheel, a clamping device receptive of an unground blank and adapted to expose a portion thereof to the action of the grinding wheel, means operable upon the completion of the grinding of the exposed portion of the blank, to automatically move the same to expose another unground portion thereof, electro-magnetic means to control said last named means, and a pattern associated with said blank to complete an electrical circuit through said electro-magnetic means at predetermined intervals.

2. In combination with a lens grinding machine having a constantly rotating grinding wheel, a clamping device receptive of an unground blank and adapted to expose a portion thereof to the action of the grinding wheel, and means operable upon the completion of the grinding of the exposed portion of the blank, to automatically move the same to expose another unground portion thereof, said means including a train of gears to rotate said clamping device, electro-magnetic means to control said train of gears, and a pattern associated with said blank to complete an electrical circuit through said electro-magnetic means at predetermined intervals.

3. In combination with a lens grinding machine having a constantly rotating grinding wheel, a clamping device receptive of an unground blank and adapted to expose a portion thereof to the action of the grinding wheel, and means operable upon the completion of the grinding of the exposed portion of the blank, to automatically move the same to expose another unground portion thereof, said means including means to rotate said clamping device, a clutch engageable with the last named means, electromagnetic means to control said clutch, and a pattern associated with said blank to complete an electrical circuit through said electro-magnetic means at predetermined intervals.

4. In combination with a lens grinding machine having a constantly rotating grinding wheel, a clamping device receptive of an unground blank and adapted to expose a portion thereof to the action of the grinding wheel, and means operable upon the completion of the grinding of the exposed portion of the blank, to automatically move the same to expose another unground portion thereof, said means including a train of gears to rotate said clamping device, a clutch engageable with said train of gears, electro-magnetic means to control said clutch, and a pattern associated with said blank to complete an electrical circuit through said electro-magnetic means at predetermined intervals.

5. In combination with a lens grinding machine having a constantly rotating grinding wheel, a clamping device receptive of an unground blank

and adapted to expose a portion thereof to the action of the grinding wheel, and means operable upon the completion of the grinding of the exposed portion of the blank, to automatically move the same to expose another unground portion thereof, said means including means to rotate said clamping device, electro-magnetic means to control said last named means, an open electrical circuit through said electro-magnetic means, said circuit including a contact plate, and a pattern associated with said blank engageable with said contact plate at predetermined intervals to complete said electrical circuit.

6. In combination with a lens grinding machine having a constantly rotating grinding wheel, a clamping device receptive of an unground blank and adapted to expose a portion thereof to the action of the grinding wheel, and means, operable upon the completion of the grinding of the exposed portion of the blank, to automatically move the same to expose another unground portion thereof, said means including a train of gears to rotate said clamping device, electro-magnetic means to control said train of gears, an open electrical circuit through said electro-magnetic means, said circuit including a contact plate, and pattern associated with said blank engageable with said contact plate at predetermined intervals to complete said electrical circuit.

7. In combination with a lens grinding machine having a constantly rotating grinding wheel, a clamping device receptive of an unground blank

and adapted to expose a portion thereof to the action of the grinding wheel, and means, operable upon the completion of the grinding of the exposed portion of the blank, to automatically move the same to expose another unground portion thereof, said means including means to rotate said clamping device, a clutch engageable with said last named means, electro-magnetic means to control said clutch, an open electrical circuit through said electro-magnetic means, said circuit including a contact plate, and a pattern associated with said blank engageable with said contact plate at predetermined intervals to complete said electrical circuit.

8. In combination with a lens grinding machine having a constantly rotating grinding wheel, a clamping device receptive of an unground blank and adapted to expose a portion thereof to the action of the grinding wheel, and means, operable upon the completion of the grinding of the exposed portion of the blank, to automatically move the same to expose another unground portion thereof, said means including a train of gears to rotate said clamping device, a clutch engageable with said train of gears, electro-magnetic means to control said clutch, an open electrical circuit through said electro-magnetic means, said circuit including a contact plate, and a pattern associated with said blank engageable with said contact plate at predetermined intervals to complete said electrical circuit.

ARTHUR LEMAY.
